UNITED STATES PATENT OFFICE.

GUY B. COLLIER, OF KINDERHOOK, NEW YORK.

ROTARY TOOTH-BRUSH.

1,318,647.

Specification of Letters Patent.

Patented Oct. 14, 1919.

Application filed September 5, 1917. Serial No. 189,795.

To all whom it may concern:

Be it known that I, GUY B. COLLIER, a citizen of the United States, residing at Kinderhook, in the county of Columbia and State of New York, have invented certain new and useful Improvements in Rotary Tooth-Brushes; and I do hereby declare the following to be a full, clear, and exact description of the invention, such as will enable others skilled in the art to which it appertains to make and use the same.

The present invention relates to rotary brushes and more particularly to brushes of this character employed for cleaning teeth.

In tooth brushes of this character as commonly constructed the operating mechanism is embodied directly in the brush, making it cumbersome and difficult to operate. In addition, with those brushes in which the rotation is secured by a manual operation of the mechanism, it is extremely difficult, if not impossible, to at the same time rotate and guide the brush.

One object of the present invention is to provide a rotary tooth brush of an improved form which is compact in construction and may be handled with the utmost facility.

A further object of the invention is to so improve the operating mechanism for the brush that the direction of rotation of the latter may be conveniently controlled by the operator and immediately reversed when desired.

With these objects in view the several features of the invention consists in certain novel features of construction, combinations and arrangements of parts hereinafter described and claimed, the advantages of which will be obvious to those skilled in the art from the following description.

In the drawings illustrating the preferred form of the invention, Figure 1 represents a view of the improved brush and operating mechanism attached to the usual faucet with the driving shaft for the brush broken away; Fig. 2 is a longitudinal section in elevation of the water motor for operating the brush attached to the faucet; Fig. 3 is a view similar to Fig. 2 but taken at right angles; Fig. 4 is a detail illustrating a longitudinal section of the rotary brush with the reversing mechanism embodied therein; Fig. 5 is a detail illustrating a view of one portion of the detachable connection for the

driving shaft; Fig. 6 is a detail showing a view of the complementary portion of the detachable connection; Fig. 7 is an end view of the connection shown in Fig. 6; Fig. 8 is a detail illustrating a modified form of connection for attaching the water motor to the faucet; and Fig. 9 is a plan view, partly in section, of the connection shown in Fig. 8.

The present invention contemplates the combination with a rotary tooth brush of means attached to a faucet for operating the brush, and a flexible driving connection between the operating means and the brush. In the simplest and most efficient form of the invention which has yet been devised a water motor is detachably connected to the open end of a faucet and operates a flexible shaft of the desired length, which is connected at its opposite end with the rotary brush. In order to permit the direction of rotation of the brush to be conveniently changed when desired, reversing mechanism is embodied in the brush, and is controlled by a finger lever so arranged as to permit the instant manipulation of the reversing mechanism. The provision of this mechanism is of considerable importance as it permits an immediate change in the direction of rotation of the brush as the position of the latter is shifted to cause the portion of the brush in contact with the teeth to move away from the gums. For example, if the brush is held in contact with the upper row of teeth it will be rotated to cause the surfaces of the brush to contact with the teeth to move downwardly, whereas if the brush is in contact with the lower row of teeth the rotation will be in a direction to cause the contacting surfaces of the brush to move upwardly. In a like manner, the direction of rotation of the brush may be conveniently reversed when cleaning teeth on opposite sides of the mouth. Thus, by manipulating the brush so that the direction of rotation is always in a direction away from the gums and toward the end of the teeth, the removal of particles from between the teeth is insured without cutting or bruising the gums.

In the illustrated embodiment of the invention the water motor is provided with a casing 10 having an intake 11 adapted to be connected with the end of a water faucet 12. As shown clearly in Figs. 1 and 2 of the

drawings, this faucet is of the usual form having a curved depending end 14 and a valve handle 15. The intake 11 of the motor is adapted to receive the lower end 16 of a 5 connecting tube 17 which is secured to the faucet through a flexible connection 18 of rubber or other suitable material. The connection 18 is provided with an annular bead 19 which receives a flange 20 formed upon 10 the upper end of the sleeve and is clamped to the sleeve by a metal band 22 having lugs 23 which are drawn together in the usual manner by a clamping bolt 24. The rubber connection is conveniently clamped to the 15 faucet through similar clamping bands 25 and 26 which surround the rubber tubing and clamp the latter to the faucet, as shown clearly in Figs. 1 and 3. The lower end 16 of the connecting tube forms a convenient 20 means for properly positioning the motor with relation to the faucet and at the same time affords a substantially leak-proof joint for conveying water from the faucet to the interior of the motor casing. In order to 25 provide a detachable connection for securing the casing 10 in operative position as shown in Fig. 2, a latch 30 is fulcrumed at 31 upon the side of the motor casing and is provided with an upper end 32 adapted to project over the tops of the lugs 23 and lock 30 the casing in position with the end 16 of the tube inserted within the intake 11 of the casing. With this construction the motor may be instantly attached to or detached 35 from the faucet, leaving the connecting sleeve in place, which does not interfere in any manner with the flow of water from the faucet.

The motor casing contains a water wheel 40 supported upon a shaft 36 journaled in bearings 37 formed in opposite sides of the casing and having blades 38 extending therefrom into the path of the water. As shown 45 clearly in Fig. 2, the water is discharged from the intake 11 downwardly through a discharge passage 40 formed beneath the intake. This construction forms an exceedingly simple and compact mechanism for utilizing the water which flows from the 50 faucet to rotate the shaft 36, the construction of the motor enabling the discharge of water to take place directly beneath the open end of the faucet. The motor shaft 36 is connected to a flexible drive shaft 42 through 55 a coupling comprising a disk 43 secured to the flexible shaft in any suitable manner and having a pair of pins 44, which are received in corresponding recesses 45 formed in a complementary driving member 46 secured 60 to the motor shaft 36, as shown clearly in Figs. 5 to 7, inclusive. With this construction the driving shaft may be disconnected from the water motor whenever desired. The opposite end of the flexible 65 drive shaft 42 is connected with a shaft 50

journaled within a casing 51 forming a part of the brush handle. This connection is made in any usual manner, as indicated clearly in Figs. 1 and 4. The drive shaft is inclosed in a flexible tube 47, which is provided with a bushing 48 in which the end of the drive shaft 42 is journaled in the usual manner.

The handle of the brush is formed by a tube 53 which is secured to the casing 51 and incloses a shaft 56. The casing 51 is provided with a cover plate 57 threaded thereto and having a boss 58 for the reception of the tubular handle 55 and also forming a bearing for the inner end of the shaft 56, 70 the outer end of which is supported by a bearing block 59 secured in the end of the tube 53. The brush shaft 56 is rotated in either direction through a pair of oppositely disposed bevel pinions 60 and 61 secured to the shaft 56 and adapted to engage with a bevel gear 62 secured to the inner end of the shaft 56 within the casing 51. The reversal of rotation of the shaft 56 is accomplished by causing either one of the bevel drive pinions 60 or 61 to mesh with the bevel gear 62. To this end a sleeve 63 is mounted upon the shaft 56 between the two pinions and is provided with a lug 65 pivotally connected to the outer end of a shift arm 64. The arm 64 is secured to a shaft 66 having a finger lever 67 secured thereto outside of the casing 51. The finger lever, as shown clearly in Figs. 1 and 4 of the drawings, is supported beneath the tubular handle 55 and 80 the operating end 68 is conveniently located so that a slight lateral pressure will swing the lever sufficiently to shift the driving pinions. This construction permits the brush to be supported and operated with the 85 same hand, the thumb or one of the fingers being utilized to shift the lever 67 when desired.

In order to permit the convenient substitution of one brush for another an elongated hub 70 is adapted to be forced on to the tapered end 71 of the shaft 56. The hub is provided with the usual sets of bristles 72 which may be of the proper shape and stiffness desired. The lips and interior 90 of the mouth are protected during the insertion and use of the brush within the mouth by a guard member 73 secured to the tubular handle 55 and extending lengthwise of the brush to a point slightly beyond the end, as shown in Figs. 1 and 4. This guard protects the back side of the brush and prevents the rotating bristles from contacting with the mouth.

It will be obvious to those skilled in the 95 art that the present construction may be manipulated to clean the teeth with less exertion than the ordinary brush and at the same time the rotation of the brush is under the instant control of the operator so that 100

the bristles shall always move in a direction best adapted to clean the particular teeth with which the brush contacts.

In the form of the invention shown in Figs. 8 and 9 a modified connection is employed for attaching the water motor to the faucet, which permits the convenient detachment of the connecting tube from the faucet. In this construction a rubber connecting tube 75 is attached at its lower end to a water intake 76 having a flange 77 and formed upon the upper end of the motor casing. A clamping band 78 grips the lower end of the tube to the intake 76. The upper end of the tube is adapted to surround the lower end of the faucet 12 and is provided with a clamping band 79 connected to the clamping band 78 by an upright arm 80 to preserve the position of the two bands relative to the tube. The band 79 is provided with lugs 81 which may be conveniently drawn together by a clamping screw 82 having a winged head 83. With this construction the water motor 10 is conveniently attached to the lower end of the faucet by inserting the upper end of the tube 75 over the faucet and tightening the clamp screw 82. In a like manner the motor is detached from the faucet by loosening the clamp screw.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A rotary brush, having in combination a brush head, a tubular handle supporting the head, a shaft connected to the head, means supported by the handle for rotating

the shaft in opposite directions, a motor and a flexible drive shaft connecting the motor 45 with the reversible driving mechanism.

2. A rotary brush comprising a tubular handle, a shaft journaled within the handle, a brush head secured to the shaft, a casing connected to the end of the handle, a reversing mechanism located within the casing and adapted to drive the shaft, and a control lever for the reversing mechanism supported in proximity to the handle.

3. A rotary brush comprising a tubular handle, a shaft journaled within the handle, a brush head detachably connected with the shaft, a casing secured to the handle, reversing mechanism located within the casing and adapted to rotate the shaft, and an oscillatory lever for controlling the reversing mechanism which extends substantially lengthwise of the handle in a position conveniently accessible to the operator.

4. A rotary brush comprising a tube, a shaft journaled within the tube, a casing secured to the tube, a gear secured to the shaft within the casing, a second shaft journaled within the casing, a pair of gears secured to the second shaft, an oscillatory lever supported outside of the casing, and connections between the oscillatory lever and second shaft for sliding the shaft axially within the casing to cause either of the gears to mesh with the gear upon the first mentioned shaft.

5. A rotary brush comprising a handle, a brush head supported by the handle, a water motor, driving connections between the water motor and brush head, a tube adapted to be attached to a faucet, a connecting sleeve secured to the tube, and a latch pivoted upon the motor and adapted to connect the motor to the tube.

GUY B. COLLIER.
